COVER FOR CURB BOXES AND THE LIKE

Filed May 2, 1928

INVENTOR:
V. E. BEAGLE,
BY *H. Woodward*,
ATTORNEY.

UNITED STATES PATENT OFFICE

VICTOR E. BEAGLE, OF ARLINGTON COUNTY, VIRGINIA

COVER FOR CURB BOXES AND THE LIKE

Application filed May 2, 1928. Serial No. 274,618.

The invention has for an object to provide a novel form of cover suitable for curb boxes particularly (although applicable in many other situations), which may be supplied as 5 a standard unit, but adapted also to use as a replacement cover for various forms of curb boxes designed for the use of other covers. It is a particular aim of the invention to provide such a cover which will utilize various lugs 10 or the like which are now provided on a number of standard forms of curb boxes to enable my cover to be secured firmly in place upon such various curb boxes without the use of the fastening screws which these curb 15 boxes customarily require in order to secure the covers in place.

It is a special aim also of this invention to provide a cover which will adapt itself automatically to various sizes and kinds of curb 20 boxes without requiring modification of its structure, nor tooling of any parts to enable it to be applied.

Additional objects, advantages and features of invention reside in the construction, 25 arrangement and combination of parts as will be more particularly described herein-after, and shown in the drawings, wherein

Figure 1 is a top view of a cover.

Figure 2 is a modification thereof.

Figure 3 is a perspective view showing the 30 lower part of the device.

Figure 4 is a similar perspective view at right angles to Figure 3.

Figure 5 is a similar view of a modification.

Figure 6 illustrates one manner of using the article,

While Figure 7 shows a further use of the 40 article, particularly where the entire bell-flange has been removed from a curb box top section and no lug is left upon the interior of the box.

There is illustrated a cover which is adapted 45 to be cast integrally in one piece and it comprises a planiform top, body or plate 10 of circular shape centrally recessed at one side and having a pentagonal nut head 11 integral thereon so as to enable the device to be turned by the standard service man's wrench ordinarily employed on curb box cover bolts.

This circular plate 10 is of a suitable size adapted to cover several different sizes of curb boxes by resting upon the bell-flange at the top of the ordinary box in each instance. In such a box also, a flange 12 is customarily 55 provided, which is apertured and threaded to receive a bolt through a standard cover in a way which is familiar in the art.

Upon the lower side of the plate 10 of my cover I have provided at one side a concentric, downwardly projected flange segment 14 extending over an area of about 120 degrees, more or less, the outer side being nearly perpendicular to the plate 10 as practicable while yet permitting ready casting, 65 while its inner side is sloped inwardly, so that it is thickened slightly at its base. Inwardly of this flange 14 an inclined portion 15 is formed on the lower side of the plate by thickening thereof, this part having somewhat the form of a segment of a cone, but not perfectly conical, as its inclination with respect to the plate varies at different parts spaced circumferentially. Also formed integrally on the thickened part of this part of 70 the body adjacent the inclined portion 15 there is a cooperating flange 16, which is substantially in the form of a segment of a helicoidal web, which, in addition to its spiral nature has also an inclination radially with 75 respect to the plane of the plate 10. It should be noted that both this helicoidal element 16 and the conical portion 15 are eccentric to the center of the plate 10, although their outer boundaries or extreme parts terminate so as to lie within a projected cylinder concentric with the top plate 10, and coincident with the outer face of the depending flange 14 before mentioned.

It is also important to note that the junction between the inclined flange 16 and the part 15 is rounded, and is located closely adjacent the axis of the plate 10 at one side, while it extends outwardly toward the periphery of the plate at the opposite part of 90 the flange 16, so as to be gradually convergent toward the periphery of the plate 10. The direction of convergence is counter-clockwise when considered from the top of the appliance, so that when the plate 10 is set 95 100

upon the top of a curb box and rotated in a clockwise direction, the flange or lugs upon the inside of the curb box may readily enter the more open space between the flange 16 and sloping surface 15, finally engaging upon the upper side of the flange 16, so as to cause the cover to be drawn downward snugly upon the top of the curb box, and in addition, by reason of the radial slope of the flange 16, my cover will be pressed bodily away from the engaged projection so that the downwardly projected flange 14 will be pressed against the far side of the curb box, causing the lower parts of my cover to become finally wedged 15 between the lug of the curb box and the far side of the box.

The size of my device may of course be varied to enable the application of the invention in other situations, and the adaptation 20 thereof to other uses will be readily understood by the disclosure presented.

In order to reduce the weight of the article, it is possible to recess the flange 14 after the manner illustrated in Figure 5.

25 While in the present instance the cover is shown as adapted to rest upon the upper edge of the curb box, still other arrangements may be employed.

It is particularly to be noted that by the 30 construction presented the cover will after application be held snugly and with a minimum of loose play. Thus, if a lifting force be applied to the edge of the cover radially outward of the depending flange 14, the point of 35 engagement of the lug of the box 10 will act as a fulcrum causing the lower part of the flange 14 to bind against the inner side of the box and preventing the cover from lifting relatively to the box. At the opposite side 40 of the cover any lifting tendency will be opposed directly by the flange 16. Under lifting stress on the lid at other points, components of both resistent effects will be manifest, as may be understood.

45 It is one of the important advantages of my invention that it is applicable to boxes heretofore manufactured for use with other covers, when the fastenings or lugs have become broken, and when it is no longer possible to secure the regular cap in place thereon. It is possible to utilize my cover when portions of the curb box are broken away at the upper edge. It is not necessary for the regular lug or flange cast in the curb box for securing the 50 cover to be perfect, but if only a portion remains, it will be engaged properly to secure the cover in place. It is a further important advantage that by the structure presented the lug or flange on the curb box which is utilized 55 to retain my cover in place does not have to be at a particular height from the top of the box, but projections at various distances from the top will be properly engaged.

In order to secure the cover in adjusted 60 positions if desired, I have provided a con-

centric series of apertures in the plate 10 through one of which nail, screw or pin may be inserted so as to pass closely as possible behind the lug 13 or other projection on the curb box engaged by the flange 16. This inserted member will engage the lug or other projection in case the cover turns counter clockwise.

In the use of this appliance it is possible to utilize a curb box the entire top portion of which has been broken away, as shown in Figure 7. The edge of the flange 16 is so positioned with respect to the part 14 that when they are inserted and rotated within the body of the curb box the flange 16 will engage against the lower side of the thread rib customarily formed in this body portion of the box. By unscrewing the upper section of the curb box slightly to compensate for the part which is broken away, my cover may be caused to lie flush with a pavement, the same as with an entire curb box.

While the flange 16 is described as an eccentric helicoidal element, the eccentricity relates to the axis on which it is constructed and the periphery of the flange may terminate concentrically with the cover or with the member 14.

I claim:—

1. A curb box cover comprising a top, and an eccentric helicoidal flange formed integrally upon the lower side thereof having throughout a steep inclination radially divergent from the plane of the top, the lower part of said helicoidal flange having the greatest radius.

2. The structure of claim 1 in which a downward projection is formed upon the top opposite from said flange, for coaction therewith, to enable the device to be wedged between the inner face of a box and a box projection when the latter is engaged by said helicoidal flange.

3. A curb box cover comprising a planiform top portion, a substantially concentric depending flange formed integrally thereupon at one side, and a helicoidal flange segment formed inwardly thereof extending toward the opposite side of the top, said helicoidal flange being eccentric to the top and having throughout a steep inclination radially of the top so as to be divergent from the top, whereby the top engaging a box projection by relative rotation will thrust the first-named flange against the side of the box and also draw the top down upon the box.

4. The structure of claim 3 in which said top is provided also with a part sloping inwardly and downwardly and forming a junction with the said helicoidal flange.

5. The structure of claim 3, in which the first named dependent flange extends over a substantial arc upon the cover and the part of maximum radius at the junction of said helicoidal flange with the top being adjacent

a diametrical line on the cover from one termination of said dependent flange.

6. The structure of claim 1 in which a downward projection is formed upon the top oppositely from said flange for coaction therewith, as described, the periphery of the flange being positioned with respect to said downward projection so as to engage loosely within the body of an interiorly and spirally ribbed curb box between the spiral ribs thereof.

10 In testimony whereof I affix my signature.
VICTOR E. BEAGLE.
